Primary Examiner — Thomas Johannes*Assistant Examiner* — Chelsea Sealey(74) *Attorney, Agent, or Firm* — Banner & Witcoff, Ltd(57) **CLAIM**

The ornamental design for a handset rear cover, as shown and described.

DESCRIPTION

FIG. 1 is a perspective view of a handset rear cover showing my new design;

FIG. 2 is a front elevational view thereof;

FIG. 3 is a right side view thereof;

FIG. 4 is a left side view thereof;

FIG. 5 is a top view thereof;

FIG. 6 is a bottom view thereof; and,

FIG. 7 is an elevational view showing the environmental structure of a handset.

The broken lines showing the environment of a handset in the figures and the unshaded regions therein are for illustrative purposes only and form no part of the claimed design.

1 Claim, 5 Drawing Sheets(56)
